UNITED STATES PATENT OFFICE.

HENRY G. FRENCH, OF SCHENECTADY, NEW YORK, ASSIGNOR TO GENERAL ELECTRIC COMPANY, A CORPORATION OF NEW YORK.

PROTECTIVE DEVICE.

1,374,727.

Specification of Letters Patent. Patented Apr. 12, 1921.

Application filed October 25, 1919. Serial No. 333,248.

To all whom it may concern:

Be it known that I, HENRY G. FRENCH, a citizen of the United States, residing at Schenectady, county of Schenectady, State 5 of New York, have invented certain new and useful Improvements in Protective Devices, of which the following is a specification.

My invention relates to protective devices, particularly to relays and has for its object 10 to provide a relay of the induction type which is operative in response to a predetermined abnormal condition in a positive and definite manner, which will move positively to contact controlling position and 15 which embodies other features to be described more in detail hereinafter.

In relays of the induction type in which a rotatable armature is controlled by torque and counter-torque elements, it is necessary 20 to compensate for the increase in effect of the counter-torque element when the armature is actuated by the torque element. Without compensation a current just enough to start the armature rotating is insufficient 25 to carry the armature positively to complete its path of movement as the armature will "float" or move to a position where the effects of the torque and counter-torque elements balance. Again the "pick-up" value 30 of current for which the relay is set to operate may not positively start the armature rotating due to the small increase in torque over the counter torque.

According to my invention, I overcome 35 these disadvantages by providing a relay which has a positive and definite pick-up when the current reaches a predetermined value and which is carried positively and definitely to complete its path of movement 40 on that value of current or that driving torque sufficient to initially start the armature in rotation.

The novel features which I believe to be characteristic of my invention will be definitely indicated in the claims appended 45 hereto while the features of construction and mode of operation will be understood by reference to the following description taken in connection with the accompanying 50 drawing in which:

Figure 1 shows, in perspective, a relay embodying my invention; Fig. 2 shows, in perspective, a relay embodying a modified form of my invention, and Fig. 3 is a

graphic illustration of the operating characteristics of my improved relay. 55

In Fig. 1 the relay of my invention comprises a rotatable armature member 1, carried by a shaft 2, which carries a movable contact 3 adapted to be moved into and out of engagement with coöperating fixed contacts 4 by rotation of the armature, to control an auxiliary circuit. This circuit may operate a trip coil or auxiliary relay to open the circuit protected by the relay of my invention. The rotatable armature 1 is actuated and controlled by a torque-producing element 5 tending to drive or rotate the armature 1 in contact-closing direction, and also by a counter-torque or restraining element 6 producing an opposing or counter torque tending to rotate the armature 1 in the opposite direction. Normally the effect of the counter-torque element 6 predominates to hold the armature against a stop 7. 75

The torque-producing element 5 is preferably of the electromagnetic type consisting, as shown, of a U-shaped magnetic member 8 upon which is mounted actuating windings 9 connected in series. Upon the 80 pole tips of the magnetic member 8, between which the armature is movable, are shading coils 10 to provide a rotative effect on the armature. The counter-torque element 6 is also preferably of the electromagnetic type 85 comprising a U-shaped magnetic member 11 with actuating windings 12 connected in series and in a series circuit with windings 9 of the torque element 5. The element 6 is mounted at the opposite side of the armature 1 from the torque element 5 and is provided with pole tips between which the armature is movable. These pole tips are provided with shading coils 13 which are 90 relatively movable by an adjusting means 95 14 to vary the counter torque as desired.

The counter-torque element 6 is also provided with a positive pick-up device consisting of means for automatically short circuiting the flux across the pole tips and 100 hence the flux cutting the rotatable armature. This means consists of leakage poles 15 having an air gap substantially greater than the gap between the pole tips. This gap is adapted to be bridged to form a 105 shunt path for the flux in response to predetermined conditions and thus weaken the effect of the counter-torque element. For

enabling the leakage poles to form a shunt path, I provide a plunger 16 extending through the lower leakage pole 15 and adjustably mounted in a casing 17 secured 5 to the magnetic member 11. The position of the plunger or bridging member 16 may be varied to increase or decrease the air gap between the leakage poles by an adjusting means 18 which also serves to 10 adjust the position of the plunger so that it will pick up and bridge the leakage poles 15 in any predetermined value of flux or current. The coils 9 and 12 of the elements 5 and 6 are connected in series in the secondary circuit of a transformer 19, the primary of which is responsive to the current on the line 20 to be protected.

The operation of my relay may be described as follows: normally the current in 20 windings 9 and 12 is such that a small flux is created in magnetic members 8 and 11, creating opposing torques on the armature 1. The effect of the counter-torque element 6 normally predominates to hold the 25 armature against stop 7. When the current in conductor 20 reaches a predetermined amount, a proportional current flows through windings 9 and 12 increasing the flux in members 8 and 11, and hence the 30 torque and counter torque exerted by elements 5 and 6 respectively. The flux in counter-torque element 6 upon this predetermined value of current, for which the device is set to operate, is sufficient to operate 35 the pick-up device attracting plunger 16 and moving it into engagement with upper leakage pole 15. The plunger thus bridges the leakage poles and forms a path for the flux in shunt to that across the pole 40 tips of element 6. The result of the attraction of the plunger 16 is to instantly short circuit the flux creating the counter torque on armature 1 reducing thereby the effect of the counter-torque element. The 45 driving element 5 thereupon overcomes the counter-torque element and positively moves the armature 1 to complete its path of movement and bring contacts 3 and 4 into engagement. The engagement of contacts 50 3 and 4 functions to enable the circuit 20 to be opened. A comparatively light spring 21 is connected to the shaft 2 adapted to be tensioned by the movement of the armature 1 and which operates to return the armature to its initial position when current to the control elements 5 and 6 is interrupted.

It is thus apparent that as soon as the current and hence the flux in the counter-torque element 6 reaches a predetermined 60 amount, the pick-up device automatically operates with a positive action to reduce the effect of the counter-torque element and enable the torque element 5 to effectively predominate and move the armature 1 definitely and positively into contact-closing

position. All danger of floating is thereby definitely eliminated. The pick-up value and hence the point of operation of the relay may be controlled by adjusting the air gap between the leakage poles which is 70 accomplished by adjusting the position of the plunger. The armature 1 may be provided with a drag element, such as a permanent magnet of well known construction, if such is desired, for giving a time interval 75 in the operation of the relay. I have not shown such an element in Fig. 1 for purposes of clearness.

In Fig. 2 I have shown a modified form of my invention in which the rotatable 80 armature member 1 is controlled by a torque element 5 and a restraining or counter-torque element. In this case the counter-torque element comprises the spring 21. The movement of armature 1 is delayed by 85 the permanent drag magnet 22. The driving or torque element 5 is of the electromagnetic type having a laminated magnetic member 23 upon which is wound the actuating winding 24 controlled from the circuit to be protected. The armature 1 is rotatable between the pole tips of the magnetic member 23 which are provided with shading coils of well known construction. In this construction, the magnetic member 90 95 23 is provided with an air gap which reduces the flux set up in member 23 and hence reduces the torque produced on the armature 1. The air gap is adapted to be automatically closed by a movable plunger 25 to 100 increase the flux set up by the element 5 in response to predetermined abnormal conditions. The position of the plunger and hence the size of the air gap may be varied by adjusting means 26 to close the magnetic 105 circuit of member 25 under any predetermined value of flux or current in winding 24. In the arrangement shown, I provide the movable core or plunger 25 as one leg 110 of the magnetic member 23 movably positioned and extending through the lower portion 27 of the member. The plunger is surrounded by a suitable casing 28.

Normally the effect of counter-torque element 21 predominates to hold the armature against the stop 7. Due to the reluctance of the magnetic current of member 23, little flux passes the pole tips and little driving torque is exerted on the armature 1. Upon increase in current in winding 24, the flux in member 23 increases until it is sufficient to attract plunger 25 which moves to close the air gap in the circuit of member 23 thereby greatly increasing the flux in member 23. The adjustable plunger 25 serves as a pick-up device to greatly increase the torque exerted by the driving element 5, upon that value of current for which the device is set to operate. When the pick-up value of current is reached, the torque exerted by the 125 130

element 5 positively overcomes the spring or counter-torque element 21 and moves the armature positively and definitely in contact-controlling direction until contacts 3 and 4 are brought into engagement. Upon the opening of the circuit to be protected, winding 24 is deenergized, plunger 25 falls to its initial position and the armature 1 is returned to its initial position by the counter torque exerted by spring 21.

In order to effect a quick return of plunger 25 shown in Fig. 2 and also of plunger 16 shown in Fig. 1, I may provide any known means to prevent sticking of the plunger due to residual magnetism. For this purpose a thin brass washer may be used on the plunger or any other similar device.

In Fig. 3 I have shown in a graphical manner the time current curve of the relay embodying the principles of my invention. Depending on the setting of the pick-up device, which is noted by the vertical line $a-a$, the relay is held inoperative until the pick-up value of current is reached. Upon the occurrence of the pick-up value of current, the relay is positively set into operation and completes its operation definitely and with a positive action. The effect of the pick-up device is, therefore, to eliminate that portion of the time current curve at the left of the line $a-a$, shown in dotted lines, and only that portion of the curve is obtained which is shown in a solid line. In this manner the selective action of relays of this type are dependable and the relays are positive in action.

What I claim as new and desire to secure by Letters Patent of the United States, is,—

1. In a relay of the induction type, the combination with a rotatable armature, a torque-producing element for moving said armature in response to currents above a predetermined amount, an element producing a counter torque normally overcoming said torque element, and adjustable means responsive to currents of any predetermined amount for varying the pick-up point of said torque-producing element.

2. A relay device comprising a rotatable armature, contacts controlled thereby, a motor element tending to rotate said armature in contact-controlling direction, a restraining element normally rendering said motor element ineffective, and means adjustable to operate in response to any predetermined value of current for causing said motor element to positively overcome said restraining element and carry said armature through its complete path of travel into contact-controlling position.

3. In an induction relay, the combination with a rotatable armature, contacts closed thereby, an electromagnetic element operative in response to current above a

predetermined amount to rotate said armature to contact-closing position, restraining means normally overcoming the effect of said element, and means adjustable to cause said electromagnetic element to overcome said restraining element and move said armature into contact-closing position at any predetermined point in the time current curve of said relay.

4. In a relay device, the combination with a rotatable armature, contacts controlled thereby, a torque-producing element for rotating said contacts in contact-controlling direction, a restraining element normally overcoming said torque element, and means adjustable to operate in response to abnormal conditions in excess of any predetermined amount for causing said torque-producing element to quickly and positively overcome said restraining element and move said armature into contact-controlling position.

5. In a relay device of the induction type, the combination with a rotatable armature, contacts controlled thereby, a motor element producing a torque on said armature in a direction to rotate the same in contact-controlling position, an electromagnetic element having a magnetic flux adapted to produce a counter torque on said armature, means responsive to currents above any predetermined amount for reducing the flux of said counter-torque element tending to effect said armature whereby said motor element predominates to quickly rotate said armature into contact-controlling position.

6. In a relay of the induction type, the combination with a rotatable armature, an electromagnetic element producing a flux tending to rotate said armature in one direction, a second electromagnetic element producing a flux tending to rotate said armature in the opposite direction but ineffective until the current exceeds a predetermined amount, means associated with said first mentioned element operative upon currents above said predetermined amount to short circuit the flux thereof to permit said armature to move quickly under the influence of said second element.

7. In a relay device, the combination with a rotatable armature, contacts controlled thereby, a torque-producing element for rotating said armature into contact-controlling position, an electromagnetic element producing a counter torque on said armature normally overcoming said torque element, main poles for said counter torque element between which said armature is movable, secondary poles for said counter-torque element outside the influence of said armature, and means whereby the normal path of the flux of said counter-torque element is through said main poles but upon the oc-

urrence of current above a predetermined amount the path of said flux is through said secondary poles.

8. In a relay device, the combination with 5 a rotatable armature, contacts controlled thereby, a torque-producing element for rotating said armature to contact-controlling position, an electromagnetic element producing a counter torque on said armature 10 which normally overcomes the effect of said torque element, poles for said counter-torque element between which said armature is rotatable, and means adjustable to operate in response to any predetermined abnormal 15 condition to reduce the flux passing through said main poles whereby the effect of said torque element predominates.

9. In a relay device, the combination with 20 a rotatable armature, contacts controlled thereby, a torque-producing element for rotating said armature to contact-controlling position, an electromagnetic element producing a counter torque on said armature which 25 normally overcomes the effect of said torque element, main poles for said counter-torque element providing a path for the flux

through said armature, and leakage poles providing a shunt path for said flux without affecting said armature, and means whereby the normal path of said flux is through 30 said main poles but upon the occurrence of predetermined abnormal conditions the path of said flux is through said leakage poles.

10. In a relay device, the combination with 35 a rotatable armature, contacts controlled thereby, a torque-producing element for rotating said armature to contact-controlling position, an electromagnetic element producing a counter torque on said armature 40 which normally overcomes the effect of said torque element, main poles for said counter-torque element providing a path for the flux through said armature, leakage poles forming a normally open shunt path for the 45 flux, and means for closing said shunt path in response to predetermined abnormal conditions.

In witness whereof, I have hereunto set my hand this 23rd day of October, 1919.

HENRY G. FRENCH.
